ICE TRAY ORGANIZATION FOR
REFRIGERATORS

James H. Miner, Meridian, Miss.

Application March 8, 1938, Serial No. 194,672

9 Claims. (Cl. 62—108.5)

The invention concerns an ice tray for use with refrigerators, and one object is to provide a tray, the main element of which will be of simple and substantially conventional form, but so arranged 5 or related to each other that by pressing or forcing the grid downwardly after the water has been frozen, the ice cubes will be separated from the contacting walls of the grid and tray in order that they readily may be removed.

10 The invention is shown in the accompanying drawing and consists in the features and combination and arrangement of parts hereinafter described and particularly pointed out in the claims.

15 Figure 1 is a side view of a tray organization embodying my invention.

Fig. 2 is an end view.

Fig. 3 is an end view of the grid.

Fig. 4 is an end view of the tray with its end 20 wall partly broken away.

Fig. 5 illustrates another form of the invention to secure the initial elevated position of the grid relative to the tray.

In the drawing 1 indicates the tray proper 25 which may be made of stainless steel or aluminum, and of a substantially conventional form having upwardly and outwardly inclined side walls as shown in Fig. 2, and also upwardly and outwardly inclined end walls as shown in Fig. 1.

30 It will be understood, however, that the invention is not limited to a tray of the form just described. It is preferably of elongated shape.

Within this tray a grid is placed consisting of a longitudinally extending partition wall 2 set up 35 on edge, and having its end edges substantially conforming to the shape of the end walls of the tray. This partition member may be in one piece from end to end, or it may be divided in the center of its length to provide an independent grid section at each end of the tray. This central partition member carries laterally extending fins or supplemental partition members 3 which extend 40 laterally from the central partition member towards each side of the tray, and divide the space up into cube forming pockets. This grid member when placed in the tray is intended to be initially elevated, as it were, above the bottom of the tray, and for this purpose suitable means or relation 45 between the parts is provided.

50 As an example of said means I show a strip 4 of yielding material such as rubber, extending along the bottom of the tray at the center portion thereof, this strip being of sufficient depth or thickness vertically to hold the grid so that the lower edges 5 of its laterally extending fins or

supplemental partition members will be elevated above the bottom of the tray when the grid is seated therein.

The lower edges 5 of the laterally extending fins are sharpened so that when the grid is 5 pressed downwardly, this being allowed by the yielding quality of the rubber strip, these sharpened lower edges will cut the ice formation lying below them, and the action will be such that the ice cubes will be loosened from the walls of the 10 tray and from the walls provided by the longitudinal partition and laterally extending fins of the grid.

As is well known, the amount of displacement 15 between the parts of the grid organization need not be but very slight in order to loosen the cubes, and this slight movement is rendered possible by the initial elevation of the grid relative to the tray by the use of the resilient strip as a 20 means for initially holding the grid slightly above the bottom of the tray. The central partition of the grid and those portions of the laterally extending fins which overlie the rubber strip are blunt so that they will merely indent or distort 25 the rubber without cutting it.

The sides of the tray may be arranged to yield as the grid is forced down into the tray. Pressure may be exerted for forcing the grid downwardly by any suitable means such as a lever which may find a fulcrum at one point of the 30 tray and extend thence over the grid, or the grid may be forced down by pressure applied in any suitable way, or by a mallet used for tapping or striking the grid at any suitable point or points thereon.

35 As above stated, the grid may be intact from end to end, or it may be divided at the center of its length. I do not limit myself to a rubber strip as the means of securing, in effect, an initial elevation of the grid within the tray member, nor 40 to the location of the strip at the longitudinal center line of the tray.

In Fig. 5 I show a modification of the invention whereby the grid instead of being elevated above the bottom of the tray by a centrally disposed yielding strip, is supported by two strips 6, one at each side of the tray in the corner between the side wall and the bottom of the tray. These strips, like the central strip above described, extend from end to end of the tray.

45 The invention is not limited to the construction shown which is illustrative of, but not restrictive upon the scope of the invention, for which reference is made to the appended claims.

50 So far as I am aware, I am the first to coordi- 55

nate a tray member and a grid member with the grid initially located above the low position or low level to which it may be moved downwardly in the tray by applying pressure thereto in a downward direction with the object of causing the grid member of suitable form to act in splitting the ice and freeing the same from its frozen contact with the walls of the grid and tray.

10 It will be understood that the lower edges of the partition members including the center bar and the laterally extending fins are sharpened throughout the major portion of their extent, excepting where the lower edges near the ends 15 of the fins rest upon the spaced apart side strips of rubber indicated at 6 in Fig. 5.

The height of the grid, or in other words, its position above or spaced apart from the upper surface of the bottom wall of the tray, may be varied. Indeed, I may employ a comparatively 20 thin sheet of rubber covering the whole bottom of the tray, this sheet of rubber being, as an instance, only $\frac{1}{16}$ ", or slightly more in thickness. The thickness may be only such as will enable 25 the grid when receiving downward pressure, or a blow from a mallet or the like, to have sufficient displacement or downward movement to dislocate the ice cubes and to shatter their connection with the opposing surfaces of the grid and tray.

30 Instead of a mallet, a suitable lever mechanism may be employed to crack the cubes loose by slightly displacing the grid downwardly relative to the tray. The tray is of the same construction, whether the force applied to the grid is in 35 the nature of a blow or pressure.

As above stated, the grid may be in sections susceptible of independent manipulation so that less than the entire contents of the tray may be cracked away from the walls for its removal, 40 leaving the remaining ice in its frozen condition.

Where a lever is used for forcing the grid downwardly, a fulcrum therefor may be provided by slipping a band or cuff onto the tray, which cuff would provide a portion overlying the tray and 45 spaced therefrom so that the end of a hand lever or tool could be thrust between the grid and the underside of said overlying portion with the end of the lever bearing on said underside, while an adjacent intermediate part of the lever would 50 bear on the center bar of the grid so that by forcing the free end of the lever downwardly the grid would be forced down also to crack the ice joint between the parts.

While I show the grid divided at a point about 55 midway of one of the cube pockets, the invention is not limited in this way, as the division may be made at any desired point.

I claim:

1. An ice tray organization for refrigerators 60 comprising a tray and a grid held above the bottom of the tray, and movable downwardly from its elevated position for dislocating the ice from the wall of the tray and grid, said grid being substantially of the same width and length as 65 the interior of the tray, and being self-centering

in respect to the tray by substantially contacting the upstanding walls thereof, substantially as described.

2. An ice tray organization according to claim 1, resilient means within the tray for initially holding the same above the bottom of the tray, said means yielding when the grid is forced downwardly towards the bottom of the tray.

3. In a tray organization according to claim 1, a grid consisting of a longitudinally extending partition having fins extending therefrom laterally towards the sides of the tray, said fins being sharpened on their lower edges.

4. An ice tray organization according to claim 1 in which a grid made up of a central longitudinally extending partition and fins extending laterally therefrom, a resilient member upon which the central portion of the grid rests, to be forced downwardly towards the bottom of the tray, the laterally extending fins being sharpened at their 2 lower edges, excepting where they overlie the yielding strip.

5. In combination a tray of elongated form, a yielding member extending lengthwise and centrally of the tray, a grid having portions with 2 blunt edges resting upon said yielding member, and with their portions free from said yielding member, sharpened at their lower edges to divide the ice when said grid is forced downwardly towards the bottom of the tray.

6. An ice tray organization for refrigerators comprising a tray and grid, means for supporting the latter in elevated position within the tray, said grid being movable downwardly under pressure from its elevated position, the said supporting means being located between the grid and the tray bottom, and being of yielding character, substantially as described.

7. An ice tray organization for refrigerators comprising a tray and a grid therein composed of 40 partitions set up on edge with their lower edges initially above the bottom of the tray, means for initially holding the grid in its initial elevated position above the bottom of the tray, said grid being movable downwardly from its initial position to cause its partitions to act upon the ice for splitting or dislocating the same, substantially as described.

8. In combination in an ice tray organization, a tray proper, a grid and resilient means along 50 the opposite walls of the tray resting upon the bottom of said tray, and supporting the grid initially above the bottom of the tray for downward movement when pressure is applied to said grid, substantially as described.

9. In combination in an ice tray organization for refrigerators, a tray proper, a grid, and a member of rubber resting upon the bottom of the tray and supporting the grid in an elevated position initially in respect to the bottom of the tray, 60 said rubber, when downward pressure is exerted on the grid, yielding to allow the walls of the grid to dislocate or split the ice, substantially as described.
